[57] CLAIM

The ornamental design for a file cabinet, as shown and described.

DESCRIPTION

FIG. 1 is a front perspective view of a file cabinet showing my new design;

FIG. 2 is a front perspective view with the drawer in open position; and

FIG. 3 is a rear perspective view of FIG. 1; the bottom of the file cabinet is conventionally flat and unornamented.

FIG. 1

FIG. 2

FIG. 3
